UNITED STATES PATENT OFFICE.

THOMAS QUINN, OF MILFORD, MASSACHUSETTS.

MACHINE FOR PRESSING SEAMS.

1,260,803.

Specification of Letters Patent. Patented Mar. 26, 1918.

Application filed April 24, 1916. Serial No. 93,151.

To all whom it may concern:

Be it known that I, THOMAS QUINN, a citizen of the United States, residing at Milford, county of Worcester, State of Massachusetts, have invented an Improvement in Machines for Pressing Seams, of which the following description, in connection with the accompanying drawing, is a specification, like characters on the drawing representing like parts.

This invention relates to a machine for pressing seams by which two pieces or sections are sewed together, and while the invention is capable of use for pressing seams of any nature, the embodiment herein illustrated has been especially designed for use in pressing the seams by which the different sections of a shoe upper are sewed together.

In sewing together the different sections of the shoe upper or the pieces of many other articles, it is customary to place the two sections to be sewed together face to face with the edges to be sewed together in alinement and then to unite the pieces by a line of through-and-through stitches which extends along adjacent the alined edges. The two sections thus sewed are then turned so that the face sides of the sections come on the outside, this operation bringing the raw edge of the seam on the inside of the article.

In the manufacture of many articles, it is desirable to press the seam when thus made so as to eliminate the rib which is formed by the seam and also to open out the seam on the outer side sufficiently to show the threads. My machine is especially designed for this purpose, and as stated above, while the device illustrated in the drawing is constructed especially to operate on the seams made in sewing together the parts going to make a shoe upper, yet the invention is not confined to this particular purpose, but is adapted generally for use where it is desired to press a seam of this nature.

In the drawings, Figure 1 is a side view of a machine adapted to press the seam formed at the back of a shoe upper;

Fig. 2 is a side view looking in the opposite direction from Fig. 1;

Fig. 3 is a top plan view;

Fig. 4 is a section on the line 4—4, Fig. 2;

Fig. 5 is a view showing two pieces of a shoe upper sewed together;

Fig. 6 shows these two sewed-together pieces opened out and illustrates the condition of the seam before it is pressed;

Fig. 7 is a view showing the result of pressing the seam;

Fig. 8 shows the operation of my device in pressing a seam.

Before describing the machine, I will refer briefly to the character of the seam which it is designed to treat.

In Fig. 5 I have shown two pieces 1 and 2 of a shoe upper, these pieces being those forming the heel and ankle portion of a shoe. During the process of making the shoe, these pieces of shoe upper are placed face to face, as shown in Fig. 5, with the edges 4 thereof in alinement, and they are then stitched together by a line of stitching 3, the stitches of which extend through and through the two alined edges 4 of the sections 1 and 2. In thus sewing the pieces 1 and 2, they are placed so that the outer faces of the leather come together and when the two pieces are opened out during subsequent operations on the shoe, the seam will present the appearance shown in Fig. 6 in which the edges 4 form an inwardly-projecting rib.

Before the shoe is completed and ready for use it is necessary to press this seam so as to flatten or eliminate this rib, this being done by separating the two edges 4 and folding them flat against the inner face of the pieces 1 and 2, as shown in Fig. 7.

The machine herein illustrated for thus pressing the seam comprises a work support on which the seamed article is supported and a combined pressing and ironing roll which is moved longitudinally of the seam and which operates not only to separate the two edges 4 and press them against the inner faces of the pieces 1 and 2, but also operates to iron the seam as it is pressed. This is accomplished by placing the seamed article on the work support with the rib formed by the seam extending upwardly therefrom and then passing the roll longitudinally of the rib so as to cause it to spread the edges thereof and roll them down against the inner faces of the pieces 1 and 2 and at the same time positively rotating said roll about its axis so that it has a surface speed greater than the speed of its advancing movement so that the surface of the roll will produce an ironing effect upon the pressed seam. The work support is shown at 5 and in the embodiment of the invention herein illustrated is especially adapted for pressing the rear seam of the shoe. The work support is in the form of an arm having a rounded upper

edge 6 that is preferably curved to correspond in general to the curvature of the edges 4 of the two pieces 1 and 2. This work support may be sustained in any suitable way 5 and is herein shown as secured to a frame 7 by which the other parts of the mechanism are supported. This work support or arm is mounted on a stud 8 secured to the frame 7 and is provided with a foot portion 9 carrying two adjusting screws 10 that engage a flange 11 extending from the frame, the purpose of these adjusting screws being to provide means for varying the angle of the arm 5 and for maintaining it rigidly in its adjusted position.

The combined pressing and ironing roll is shown at 12 and it is situated above the edge 6 of the work support 5 and is preferably made slightly concaved at its periphery. 20 This combined presser and ironing roll is journaled in a carrier constructed to move longitudinally of the arm or work support 5, and means are provided for maintaining said roll in engagement with the arm or with the 25 work supported thereby during its traveling movement, and also for positively rotating the roll as it moves and at a surface speed greater than the speed of the longitudinal movement.

30 There are various ways in which the roll might be mounted for accomplishing this result. One simple construction is herein shown wherein said roll is journaled in a holder 13 which in turn is sustained by a 35 carriage 14 constructed for movement longitudinally of the arm 5. The roll is shown as loosely mounted on a shaft 75 which is secured in the lower end of the holder 13. The carriage 14 is herein shown as slidably 40 mounted on a portion 15 of the frame 7 which extends substantially parallel to the work support 5 and is provided with means for guiding the carriage 14 in its reciprocating movement. While the carriage 14 45 and the portion 15 of the frame may have any desired construction by which the desired end is accomplished, I have illustrated in the drawings a practical but simple construction. The guiding portion 15 of the 50 frame is provided with a longitudinally-extending slot 16 and the carriage 14 is formed at its upper end with a flange 17 which overlies the upper edge of the guide portion 15 of the frame and said frame has secured thereto two laterally-extending 55 guide members 18 which extend through and operate in the slot 16. In the construction shown, the guides 18 are rolls which are loosely mounted on studs 19 that extend 60 through the carriage 14 and through plates 20 and 21 on opposite sides of the carriage, these pins 19 having nuts 22 screw-threaded to the ends thereof by which the plates 20 and 21 are tied together. With this con-

struction the carriage 14 is permitted to 65 move freely back and forth on the guide portion 15 of the frame and is guided in its movement by the coöperation of the slot 16 and the guiding members 18. If the upper edge 6 of the work support 5 were made 70 straight, as might be the case if the seam to be pressed extended along a perfectly straight edge, then the pressing roll 12 might be secured directly to the carriage 14, but where the edge 6 of the work support is 75 curved, as shown in the drawings, some provision is necessary to permit the roll 12 to follow the curved edge as the carriage moves longitudinally. I accomplish this herein by making the holder 13 to which the roll 12 is secured capable of vertical movement in the carriage 14. As herein shown this holder is in the form of a vertically-extending bar that extends upwardly through the carriage 14 and is capable of vertical 80 movement therein. In order to maintain this roll 12 in contact with the work, I provide the guide portion 15 of the frame with a guiding edge 23 which has a curved contour similar but complementary to that of the curved edge 6. The holder 13 is provided with a laterally-extending roll or stud 24 which engages the underside of the guiding edge 23 so that as the carriage 14 is reciprocated longitudinally of the guide portion 15 of the frame, the coöperation of the roll 24 with the edge 23 will cause the pressing and ironing roll 12 to follow the contour of the edge 6.

The carriage 14 may be given its reciprocating movement on the guide portion 15 of the frame by any suitable means. As herein shown, I employ a main shaft 25 which is journaled in the frame 7 and is provided with a crank arm 26 that is connected by a connecting rod 27 to the carriage 14 so that rotation of the shaft 25 will give the requisite movement to said carriage. I will preferably also provide a driving mechanism for the shaft 25 which when set in operation 100 will rotate said shaft through one complete revolution and will then bring the shaft to rest so that at each operation of the machine, the carriage 14 will be given one complete reciprocation. The shaft 25 is shown 105 as having a gear 28 thereon which meshes with and is driven by a pinion 29 on a shaft 30 which carries a driving pulley 31. The gear 28 is loosely mounted on the shaft 25 and a one-revolution clutch of any suitable 110 construction, and which is shown generally at 32, is provided by which the gear may be clutched to the shaft. 33 is a clutch-operating lever by which the clutch is rendered 115 operative. Inasmuch as any well-known clutch adapted to rotate the shaft 25 through a predetermined number of revolutions and then automatically bringing it to rest may

be used, I have not deemed it necessary to illustrate in detail any particular clutch.

I have also provided herein means for varying the pressure of the roll 12 against the work. To properly press some seams will require a greater pressure of the roll than is necessary to press other seams, depending on the character of the material. In order to thus provide for varying the pressure of the roll 12 against the work, I make the holder in which the roll is journaled in sections and interpose a spring between said sections by which the roll 12 will be yieldingly held against the seam with a pressure determined by the tension of the spring. In the illustrated embodiment of the invention the holder 13 is made with the upper and lower sections 40 and 41, the section 41 having the roll 12 journaled therein. This section 41 is provided with a laterally-extending flange or seat 42, and the upper section 40 is also provided with a laterally-extending flange 43. 44 is a spring which is interposed between said flanges. This spring is shown as held in position at its lower end by a positioning projection or stud 45 rising from the flange 42 and at its upper end it is received in a cap or housing 46 which is acted upon by a set-screw 47 operating in the flange 43. By this means the tension of the spring can be adjusted so that the roll 12 will bear on the seam with any desired pressure. This spring 44 also permits the roll 12 to yield slightly if the work varies in thickness.

As stated above, the roll 20 not only rolls over the seam to press the latter, as shown in Fig. 7, but it also is positively rotated about its axis during its movement longitudinally of the work support 5 and at such a speed relative to the longitudinal movement that an ironing effect will be produced. While various devices for thus positively rotating the roll as it moves longitudinally of the work support 5 may be employed, I would prefer to use a construction by which the positive rotation is derived from the longitudinal movement of the carriage 14. The construction shown in the drawings is a practical and efficient device for accomplishing this. The roll 12 has fast therewith a pinion 48 which meshes with a gear 49 journaled on a stud 50 that is carried in the section 41 of the holder 13. This gear 49 meshes with a rack 51 which is held from longitudinal movement but which is permitted to move vertically as the roll 12 moves vertically in conforming to the curved edge 6. Since the rack 51 has no longitudinal movement, it will be seen that the movement of the carriage 14 will cause the gear 49 to be rotated about its axis and since this gear meshes with the gear 48, the gear 48 will thus be given a positive

rotary movement. The relative size of the gears 48 and 49 is such that the presser wheel 12 is given a speed of rotation about its axis faster than that which would naturally be given to it by its rolling movement over the work and thus there is a slip-page between the surface of the wheel 12 and the work which produces an ironing effect. The roll 12, therefore, not only presses the seam, but also has the effect of ironing it.

In order to provide for the vertical movement of the rack, I propose to pivotally connect the rack at one end to the frame, as shown at 52, and to maintain the gear 49 in mesh with the rack, I provide a strap member 54 which is secured to the stud or shaft 75 for the wheel 12, and also to the stud or shaft 50 on which the gear 49 is mounted, said strap 54 having a projecting finger or roll 55 extending from its upper end and overlying the upper edge of the rack. In this way the rack and gear 49 are always maintained in mesh with each other, regardless of the vertical movements of the roll 12.

While I have illustrated the invention as adapted for pressing the rear seam of a shoe upper, yet it will be obvious that the mechanism may be used for pressing other seams. The particular shape of the work support 5 may, of course, vary somewhat, depending on the shape of the seam which is to be treated.

I claim:

1. In a device for pressing seams, the combination with a work support, of a seam-pressing roll, means to move said roll over said work support, means to rotate said roll positively as it is thus moved and at such a speed relative to its speed of movement that the periphery of the roll will have a sliding as well as a rolling contact with the seam to be pressed whereby an ironing action will be effected, and means independent from the roll-rotating means for maintaining the roll yieldingly pressed against the work.

2. In a machine for pressing seams, the combination with a work support, of a seam-pressing roll, means to move said roll over said work support, means to rotate said roll positively as it is thus moved and at a faster speed than that which would result from its rolling contact with the work whereby an ironing effect is produced, and adjustable means for maintaining said roll yieldingly pressed against the work on the work support.

3. In a device for pressing seams, the combination with a work support, of a seam-pressing roll, means to move said roll bodily over said work support and in contact with the seam to be pressed, and means actuated by such bodily movement to rotate the roll

positively as it is moved bodily but at a speed different from that which would be produced by the rolling contact between said roll and the work whereby an ironing action 5 is produced.

4. In a machine for pressing seams, the combination with a work support, of a seam-pressing roll, means to move said roll over said work support, and means actuated by 10 such movement of the roll relative to the work support to rotate the roll positively as it is thus moved and at a faster speed than that which would result from its rolling contact with the work whereby an ironing 15 effect is produced.

5. In a machine for pressing seams, the combination with a work support having a seam-supporting edge, of a presser roll, means to move said presser roll bodily along 20 said edge over which the seam to be pressed may be placed, and means to rotate the roll during its bodily movement at a speed faster than that which would result from its rolling contact with the work support.

25 6. In a machine for pressing seams, the combination with a frame having a guiding portion, of a work-supporting arm secured to said frame, a carriage slidably mounted on said guiding portion, a presser roll journaled in said carriage, means to move the carriage thereby to move the roll longitudinally of the work-supporting arm, and means to rotate said roll positively during its bodily movement.

35 7. In a machine for pressing seams, the combination with a frame having a guiding portion, of a work-supporting arm secured to said frame, a carriage slidably mounted on said guiding portion, a presser roll journaled in said carriage, means to move the carriage thereby to move the roll longitudinally of the work-supporting arm, and means actuated by the movement of the carriage to rotate said roll positively during 45 its bodily movement and at a speed greater than that which would result from its frictional contact with said work-supporting arm.

8. In a machine for pressing seams, the 50 combination with a frame having a guiding portion, of a work-supporting arm, a carriage slidably mounted on said guiding portion, a presser roll journaled in said carriage, a rack extending longitudinally of the 55 guiding portion, and a connection between said rack and presser roll by which the presser roll is positively rotated as the carriage is moved.

9. In a machine for pressing seams, the 60 combination with a work-supporting arm having a curved work-sustaining edge, of a presser roll, means to move said roll longitudinally of said edge, and to maintain it in contact with the work sustained by said 65 edge, and means actuated by such movement

of the roll to positively rotate the latter at such a speed relative to its movement longitudinally of the edge as to produce a slipping action between the roll and the work.

10. In a machine for pressing seams, the 70 combination with a frame having a guiding portion provided with a guiding slot, of a work-supporting arm having a curved work-sustaining edge, a carriage slidably mounted on said guiding portion of the frame and guided by the slot therein, a presser roll 75 yieldingly sustained in said carriage, means to move the carriage longitudinally of the work-supporting arm, and means to cause the roll to follow the curvature of the work-sustaining edge during the movement of the carriage.

11. In a machine for pressing seams, the combination with a work support having a curved seam-supporting edge over which the 85 seam to be pressed may be placed, of a presser roll, means to move said roll bodily along said edge, and means to rotate the roll during its bodily movement at a speed different from that which would result from 90 its rolling contact with the work.

12. In a machine for pressing seams, the combination with a work support having a curved seam-supporting edge over which the seam to be pressed may be placed, of a 95 presser roll, means to move said presser roll bodily along said edge, means to maintain a yielding pressure of said roll against the work during such bodily movement, and means to rotate the roll positively as it moves 100 bodily and at a speed different from that which would result from its rolling contact with the work support.

13. In a machine for pressing seams, the combination with a work support having a 105 seam-supporting edge over which a seam to be pressed may be placed, of a carriage, means to move the carriage longitudinally of the seam-supporting edge, a holder mounted in said carriage, a presser roll journaled in the holder and adapted to operate on the seam, and means for rotating said roll positively as the carriage moves.

14. In a machine for pressing seams, the combination with a work support having a 115 seam-supporting edge over which a seam to be pressed may be placed, of a carriage, means to move the carriage longitudinally of the seam-supporting edge, a holder mounted in said carriage, a presser roll journaled in the holder and adapted to operate 120 on the seam, and means actuated by the movement of the carriage to rotate said roll positively as the carriage moves.

15. In a machine for pressing seams, the 125 combination with a work support having a curved seam-supporting edge over which a seam to be pressed may be placed, of a presser roll, means to move said presser roll bodily along said edge, and means actuated 130

by the bodily movement of said roll to rotate the roll positively and at a speed different from that which would result from its engagement with the work.

- 5 16. In a machine for pressing seams, the combination with a frame having a guiding portion, of a work-supporting arm secured to said frame, a carriage slidably mounted on said guiding portion, a holder sustained 45
10 in said carriage for movement relative thereto in a direction at right angles to the movement of the carriage, a roll journaled in said holder, means to maintain the roll yieldingly pressed against the work on said arm, 50
15 and means to vibrate the carriage on said guiding portion.

17. In a machine for pressing seams, the combination with a frame having a guiding portion, of a work-supporting arm secured 20
20 to said frame, a carriage slidably mounted on said guiding portion, a holder sustained in said carriage for movement relative thereto in a direction at right angles to the movement of the carriage, a roll journaled in said holder, means to maintain the roll yieldingly 25
25 pressed against the work on said arm, means to vibrate the carriage on said guiding portion, and means to rotate said roll positively during the movement of the carriage.

- 30 18. In a machine for pressing seams, the combination with a frame having a guiding portion, of a work-supporting arm secured to said frame, a carriage slidably mounted on said guiding portion, a holder sustained in 35
35 said carriage for movement relative thereto in a direction at right angles to the movement of the carriage, a roll journaled in said holder, means to maintain the roll yieldingly pressed against the work on said arm, 40
40 means to vibrate the carriage on said guiding portion, and means actuated by the movement of the carriage to rotate said roll positively during its bodily movement.

19. In a machine for pressing seams, the combination with a frame having a guiding portion, of a work-supporting element on which the seam to be pressed is placed, a carriage slidably mounted on said guiding portion, a holder sustained by said carriage for movement relative thereto in a direction 50
50 at right angles to the movement of the carriage, a presser roll journaled in said holder, and means to move the carriage on its guiding portion, said frame having a guiding edge by which the position of the holder 55
relative to the carriage is controlled.

20. In a machine for pressing seams, the combination with a frame having a guiding portion, of a work-supporting arm having a curved work-sustaining edge, a carriage 60
60 slidably mounted on said guiding portion, a holder sustained by said carriage for movement relative thereto in a direction at right angles to the movement of the carriage, a presser roll journaled in said holder, and 65
means to move the carriage on said guiding portion, said holder having a laterally-extending projection and said frame having a guiding edge engaging said projection and by which the position of the holder relative 70
70 to the carriage is controlled.

21. In a machine for pressing seams, the combination with a frame having a guiding portion, of a carriage slidably mounted on said guiding portion, a work-supporting element having a work-sustaining edge which is non-parallel with the line of movement of the carriage, a holder mounted in said carriage, a presser roll journaled in the holder, and means to cause the presser roll 80
80 to have a yielding engagement with the work sustained on said edge as the carriage moves.

In testimony whereof, I have signed my name to this specification.

THOMAS QUINN.

Copies of this patent may be obtained for five cents each, by addressing the "Commissioner of Patents, Washington, D. C."

It is hereby certified that in Letters Patent No. 1,260,803, granted March 26, 1918, upon the application of Thomas Quinn, of Milford, Massachusetts, for an improvement in "Machines for Pressing Seams," errors appear in the printed specification requiring correction as follows: Page 4, line 18, claim 5, after the word "edge" insert the words *over which the seam to be pressed may be placed*; same page and claim, lines 20 and 21, strike out the words "over which the seam to be pressed may be placed"; and that the said Letters Patent should be read with these corrections therein that the same may conform to the record of the case in the Patent Office.

Signed and sealed this 23d day of April, A. D., 1918.

[SEAL.]

F. W. H. CLAY,

Acting Commissioner of Patents.

Cl. 69—7.
